(57) **CLAIM**

The ornamental design for a lid with pivoting mouthpiece, as shown and described.

DESCRIPTION

FIG. 1 is a perspective view of a lid with pivoting mouthpiece showing my new design, according to an embodiment of the invention.

FIG. 2 is a front, elevation view of the lid with pivoting mouthpiece shown in FIG. 1.

FIG. 3 is a rear, elevation view of the lid with pivoting mouthpiece shown in FIG. 1.

FIG. 4 is a left, elevation view of the lid with pivoting mouthpiece shown in FIG. 1.

FIG. 5 is a right, elevation view of the lid with pivoting mouthpiece shown in FIG. 1.

FIG. 6 is a top, plan view of the lid with pivoting mouthpiece shown in FIG. 1; and,

FIG. 7 is a bottom, plan view of the lid with pivoting mouthpiece shown in FIG. 1.

The broken lines in FIGS. 1-7 are for the sole purpose of showing portions of the lid with pivoting mouthpiece, and do not form a part of the claimed design.

1 Claim, 4 Drawing Sheets
